United States Patent Office

Des. 229,814
Patented Jan. 8, 1974

229,814

PLATE OR THE LIKE

Keith D. Popovich, Corning, N.Y., assignor to Corning
Glass Works, Corning, N.Y.

Filed Sept. 21, 1971, Ser. No. 182,569

Term of patent 14 years

Int. Cl. D7—01

U.S. Cl. D7—36

Fig. 1

Fig. 2

FIG. 1 is a top plan view of a plate or the like of conventional configuration showing my new design.

FIG. 2 is an enlarged fragmental view of the plate and design shown in FIG. 1.

I claim:

The ornamental design for a plate or the like, as shown and described.
